WILLIAM KANTER, OF CLEVELAND, OHIO, ASSIGNOR TO THE PRESSED METAL PRODUCTS COMPANY, OF CLEVELAND, OHIO, A CORPORATION OF OHIO.

CLOTHESLINE PROP.

Application filed March 17, 1924. Serial No. 699,720.

This invention relates to an improved clothesline prop, and its objects are to simplify the construction; very materially reduce the cost of production; increase the durability; and facilitate and expedite the manufacture of devices of this character.

My improved prop, like others preceding it, is made up of three general elements, to-wit, a staff, a head, and a barb. The most 10 desirable prop of the prevailing types wherewith I am familiar has the head and barb constituted of malleable castings, each the head and the barb having a conical socket into which a tapered end of the staff 15 is engaged, the part being held to the staff by a nail which is engaged through a hole in the wall of the socket. Such a construction requires the tapering of the ends of the staff in order to properly fit them within 20 the sockets of the head and barb, and in the manufacture of the props it is unusual if the parts fit properly because to effect such a fit would require more time and skill than the commercial value of the prop would warrant. Consequently the heads and barbs of 25 such props are usually loose, and the one nail which holds each to the staff is very likely to loosen with the result that the parts separate. Furthermore, the production of 30 props of this character is quite expensive, the malleable iron fittings alone costing considerable aside from the special treatment of the staff for its proper engagement with the fittings.

The objections to the prevailing types of 35 props are completely eliminated in my present construction as will appear from the following description, reference being had to the accompanying drawing wherein Figs. 1 and 2 are elevational views, at right angles 40 to each other, and Fig. 3 is a sectional view, of my improved clothesline prop.

The staff, which may be made of any suitable wood, is designated 1, and to its upper 45 end is applied a head 2 and to its lower end a barb 3. The staff is of the same cross section from end to end. The stock from which the staffs are made may be finished in long pieces and cut up into the desired 50 lengths at a very nominal cost. They are then ready for the application of the heads and barbs.

The head is very simply made of two pieces of strap metal that are joined to-

gether, as by a rivet 5, to produce a neck 6. The parts may be spot welded or otherwise connected in lieu of the method illustrated. Above the neck the straps are curled inwardly, one over and spaced from the other, to effect a line confining hook 7 of usual form. Below the neck 6 the straps diverge for a distance and then continue substantially parallel to each other for engagement on opposite sides of the staff 1. The straps are perforated for nails 9, and the perforations of the strap on one side of the staff are offset with respect to those on the other, and the nails are of such a length that, when driven through the staff, the ones entering from one side clinch against the metal strap on the opposite side.

By reason of the fact that the straps may be readily separated more or less, they may be made to snugly fit staffs of varying thicknesses within a reasonable range. Consequently, the heads may be turned out in quantities, as may also the staffs and any head may be applied to any staff with assurance that the parts may be made to fit properly together without the slightest difficulty, and when the nails 9 are driven into the staff there is no possibility of the head becoming loose.

The barb 3 is constructed of a single piece of sheet metal and comprises a pyramidal portion 10 from the base of which extend cheeks 11 that are engaged on opposite sides of the staff and secured thereto by nails 12. While the base of the barb engages the flat end of the staff in such a way as to prevent 90 the barb from turning with respect to the staff, one of the cheeks 11 may be indented, as shown at 13, or have a nail or tack engaged through an aperture in it in a very obvious manner, to hold the barb more securely 95 against turning upon the nails 12.

Having thus described my invention, what I claim is:—

In a clothesline prop, the combination of a staff, a head applied to one end of said staff and consisting of two straps of metal having parts intermediate their ends connected together to provide a neck, the outer ends of said straps beyond said neck being curled inwardly, one over and spaced from the other to define a line confining hook, the inner ends of said straps below the neck diverging for a short distance and then con-

tinuing in substantially parallel relation to each other for engagement on opposite sides of said staff, each of said straps being perforated to receive nails therethrough, the 5 perforations of the straps on one side of the staff being offset with respect to those on the opposite side of the staff and the nails

being of such a length that, when driven through the staff the ones entering from one side of the staff will clinch against the metal 10 strap on the opposite side of the staff.

In testimony whereof, I hereunto affix my signature.

WILLIAM KANTER.
